US00D628590S

(12) **United States Design Patent**
Vandeberghe et al.

(10) **Patent No.:** US D628,590 S
(45) **Date of Patent:** ** Dec. 7, 2010

(54) **GROUP OF ICONS FOR A DISPLAY SCREEN**

(75) Inventors: **Keri D. Vandeberghe**, Seattle, WA (US);
Mirko Mandic, Seattle, WA (US);
Valerie Rosen, Maple Valley, WA (US)

(73) Assignee: **Microsoft Corporation**, Redmond, WA (US)

(**) Term: **14 Years**

(21) Appl. No.: **29/345,490**

(22) Filed: **Oct. 16, 2009**

(51) **LOC (9) Cl.** 32-00

(52) **U.S. Cl.** D14/492; D14/488; D14/490;
D14/491

(58) **Field of Classification Search** D14/485-495;
D18/26, 31-33; D20/11-12, 23-25, 29-32,
D20/36-38; 715/700-867, 973-977

(57) **CLAIM**

The ornamental design for a group of icons for a display screen, as shown and described.

DESCRIPTION

The FIGURE is a front view of a group of icons for a display screen showing the new design.

The broken line showing of the display screen is for environmental purposes only and forms no part of the claimed design.
